UNITED STATES PATENT OFFICE.

URI HASKIN, OF PITTSBURG, PENNSYLVANIA.

MACHINE FOR ROLLING RAILS.

SPECIFICATION forming part of Letters Patent No. 269,787, dated December 26, 1882.

Application filed May 27, 1882. (No model.)

To all whom it may concern:

Be it known that I, URI HASKIN, a citizen of the United States, residing at Pittsburg, in the county of Allegheny and State of Pennsylvania, have invented a certain new and useful Improvement in Rolling Rails; and I do hereby declare the following to be a full, clear, and exact description thereof, reference being had to the accompanying drawings, in which—
10 Figure 1 on Sheet 1 indicates a front elevation of a set of horizontal rolls mounted in sectional housingsseparable or near a plane passing between the faces of the rolls, the upper roll being so arranged in relation with its housings as to participate in any motion imparted to the latter by the hydraulic ram located below the housings. The upper section of the housings is provided with suitable locking-clutches to engage in recesses formed in the 15 inner faces of the lower section of the housings, and these clutches are adjusted to lock and unlock the sections by the action of a set of rods attached to their upper ends and to the piston-head of the hydraulic plunger. Fig. 2, 20 Sheet 2, indicates a front elevation of a set of vertical rolls mounted in vertical housings, which are constructed and arranged in such a manner as to allow the two upper sections to swing open and shut upon their pivotal connections with the lower section of the housings. These upper sections are provided with a hydraulic ram and intermediate connecting mechanism to remove and replace their cap and to impart a swinging movement to them upon their 25 pivotal connections with the lower section, and are also provided with a set of weights, which are so arranged and suspended from the cranks of the housing-pivots as to cause the upper sections to swing together after they have been opened 30 and the action of the hydraulic upon them has ceased. Figs. 3, 4, 5, 6, 7, 8, 9, 10, 11, 12, and 13 indicate the shape and position of the grooved rolls, which are used from the first to the eleventh or last pass, and show the grooves so arranged in all the rolls as to enable the rail-blank to be formed from a bloom or pile, and be rolled into a finished rail while resting on its flange instead of upon its side, as has heretofore been the case in forming and finishing the rail.
45 Like letters of reference indicate like parts wherever they occur.

My invention relates to rolling rails from a

pile or bloom at a single continuous pass, and is an improvement upon the mode of constructing and arranging mechanism adapted for that 55 purpose, and described by me in an application recently filed for improvements in "rolling metals."

Heretofore rail-blanks have always been finished while lying upon their side, and as the 60 blanks or rails possess but little ability to resist deflecting strains while lying in this position they became distorted or bent in passing through the rolls, and consequently the rails required considerable straightening before they 65 could be placed upon the market. The straightening operation requires considerable labor and produces such injurious effects upon the metal that it is believed to be the cause of nearly all the breakages of steel rails when they get upon 70 the road, for the strength is liable to be impaired by the rough treatment in bending the rail under the press with the hammer-gags cut on the flanges. (See rail specifications and rail inspection by Sandberg, page 211, vol. ix, 75 Transactions of American Mining Engineers.)

The object of my invention is therefore to bring the rail out straight, in order that all or the greater portion of the straightening operation may be avoided, and this object I obtain 80 by arranging a series of rail-rolls in close proximity to and in line with each other, so that several or all the sets may operate upon the metal at one time, and by forming the grooves in all the rail-rolls of such a form that the blank 85 or rail rests upon its flange during its passage through the train, this position imparting to it greater stiffness and ability to resist the downwardly-deflecting action of the weight of the metal. 90

In the drawings, A indicates the driving-shaft of one of the sets of vertical rolls, which are used in the train, and is journaled in a set of pillow-blocks, B B, which rest upon suitable foundations, and extend under and support the 95 bed-plates B' B', upon which the lower section, C, of the housings is mounted. This lower section, C, of the housings is bolted permanently to the bed-plates B' B', so as to be incapable of any movement, and is provided at the front 100 and back portions of its sides with journal-boxes c for the reception of the shafts or pivots c' c', which connect the upper sections of the housings with the lower. These shafts or piv-

ots c' c' pass through and are keyed permanent-
ly into the downwardly-projecting portions of
the sides of the upper sections of the housings;
or, if desired, the shafts may be made square
5 at these points and be fitted into rectangular
slots in the downwardly-projecting portions of
the sides of the upper sections; or they may
be attached thereto in any other suitable man-
ner to cause the upper sections to swing with
10 them whenever they are oscillated by the ac-
tion of their oscillating mechanism. Each of
these shafts c' is provided at both ends with os-
cillating cranks c^2 , to which the upper ends of
the crank-rods c^3 are pivoted, and the lower
15 ends of these crank-rods c^3 are each provided
with a ball of a greater diameter than that of
the crank-rods and of about the same as that
of the bore of the sleeves or open-topped cyl-
inders c^4 , which are secured to the face-plate
20 of the plunger of the ram. These sleeves c^4
are provided with a bore of sufficient diameter
to allow the plunger and face-plate of the ram
to ascend until the bottom of the sleeves strikes
against and commences to impart an upward
25 movement to the balls upon the lower ends of
the crank-rods before the sides of the rods are
forced in contact with the walls of the sleeves,
the object of this arrangement being to allow
the face-plate of the plunger to ascend some
30 distance upward without actuating the crank-
rods, and to then allow the upper ends of the
rods to swing freely with the cranks as the lat-
ter are forced around the arc of a circle in
opening the upper sections of the housings.
35 c^5 indicates a lifting rod, which is screwed at
its lower end into a lug on the forward portion
of the face-plate of the hydraulic plunger, and
is connected at its upper end to the cap-piece,
which secures together the top of the upper
40 sections of the housings. This lifting-rod c^5
passes through a slotted bearing in a lug, c^6 ,
on the forward part of the lower section of the
housings and through a slotted bearing in a
similar lug, c^7 , in the upper portion of one of
45 the upper sections of the housings, and the
upper and lower sections of the rod c^5 are
united together by a pivotal connection, c^8 , at
a point a little above the slotted bearing c^6 in
the lower section of the housings. The object
50 of this construction is to compel the lifting-
rod c^5 to move up in a direct vertical line until
the housing's cap is elevated off of the head of
the upper sections, and to then allow the cap
and upper section of the lifting-rod to swing
55 away with one of the upper vertical sections
of the housings.

D indicates the detachable housing-cap,
which is formed of a cast-iron box, rectangular
in form. The top, front, back and one side are
60 cast in one solid piece, which is open at the
bottom, and the remaining side is formed of an
iron plate, d' , which is pivoted to the top, so
that an iron cap or box, open at the bottom, is
formed, and has a swinging side, which may
65 be adjusted to increase or decrease the lower
part of the opening in the cap.

E indicates a wrought-iron ring or band,

which surrounds the lower part of the cap, and
is provided with an adjusting screw to adjust
the swinging side of the box tightly against 70
the heads of the upper sections of the housings.

F indicates the hydraulic ram or other lifting
device, operated by fluid-pressure, which may
be used for opening the housings; and f and f'
indicate the inlet and outlet pipes, respectively. 75

G G indicate a set of weights which are
suspended below the mill-floor from the ends of
the cranks, which swing the upper sections of
the housings, and are made of sufficient weight
to compel the upper sections to swing back into 80
position whenever they are relieved from the
opening action of the hydraulic.

H and H' indicate the rolls, and I I I I indicate
the roll-tightening screws. h and h' indicate
the guides, which are vertically and later- 85
ally adjustable by means of suitable vertical
and lateral adjusting guide-rods.

The driving-shaft A is provided with beveled-
gear wheels a a , which mesh into and commu-
nicate motion to the beveled-gear wheels a' a' , 90
mounted on the lower ends of the vertical
spindles which drive the lower sections, J J, of
the coupling-clutches. These vertical coupling
clutch-spindles are journaled in sleeve-boxes
95 a^2 a^2 , which are let down into the lower section
of the housings, and may be adjusted into po-
sition for varying sizes of rolls by means of the
adjusting-screws a^3 a^3 a^4 a^4 a^4 a^4 .

J' J' indicate the upper sections of the
coupling-clutches, which are securely attached 100
to the lower ends of the roll-spindles, and both
the upper and the lower sections of these cou-
pling-clutches are provided with ratchet-teeth
inclining at a sufficient angle in the direction
in which the upper sections of the housings 105
swing to enable the ready connection and dis-
connection of both sections of the clutches
during that operation.

K indicates the foundation-plates of the
horizontal-roll housings, and k k' the bed- 110
plates bolted thereon.

L indicates the lower and L' the upper sec-
tion of the housings, which are constructed so
as to be separable at or near a plane passing
between the working-faces of the rolls. 115

M and M indicate a set of locking-clutches,
pivoted at their centers in recesses in the inner
faces of the upper section of the housings, and
are pivoted at their upper ends to a set of lift-
ing-rods, which are screwed at their lower ends 120
into lugs on the face-plate of the plunger of the
ram. The lower portions of these clutches are
provided with laterally-projecting ends, which
engage in rectangular slots in the inner faces
of the lower sections of the housings, in order 125
to lock them during rolling, and are withdrawn
therefrom when it is desired to remove the top
section. A similar set of clutches are arranged
in like manner at the back of the housings and
are operated by means of a similar set of lift-
ing-rods attached to them and to the face-plate 130
of the ram.

In the arrangement of a continuous train for
rolling rails from a bloom or pile—say of seven

inch diameter—the successive sets of rolls are provided, as shown in Sheet 3, with the proper form of grooves for forming the rail-blank and finishing the rail while resting upon its flange during the passage of the metal through the train. These rolls are mounted in their housings and arranged in close proximity to and in line with each other, so that several or all the sets may operate upon the metal at one and the same time, so as to rapidly reduce the bloom or pile into a finished rail at a single continuous pass.

In the above arrangement, as indicated by Sheet 3, the first pair of rolls will be horizontal, the second vertical, third horizontal, fourth vertical, fifth vertical, sixth horizontal, seventh vertical, eighth vertical, ninth horizontal, tenth vertical, and eleventh vertical, and each set of these rolls are mounted in sectional housings, constructed as shown in Figs. 1 and 2.

In the above arrangement the first five sets of rolls are supplied with grooves to effect a reduction of the bloom or pile similar to that of the ordinary cogging-mill, as may be observed by reference to Sheet 3, and the remaining sets with grooves to effect a reduction of the billet or rail-blank into the finished rail, similar to that effected by the ordinary set of rail-rolls, the only difference being that the grooves are so arranged in the present case as to allow the metal to rest upon its flange in passing through all of them, while in the former cases the metal lay on its side in the rail, forming grooves proper.

In the operation of my improvement the horizontal and the vertical rolls being mounted in their respective forms of sectional housings are arranged in close proximity to and in line with each other, and the metal, being properly heated, is entered into the first set and rapidly passes through the train, the rail-blank formed by the first five sets resting on its flange during its passage through the remaining sets, and coming out of the last set in the form of a straight finished rail.

It will be seen that by thus preserving the flange of the rail in a horizontal plane the weight of the metal will be in a vertical line coincident with the web, which, acting as a column, will present the greatest attainable resistance to the sagging and bending of the rail.

Whenever the metal becomes clogged or jammed in the rolls and it is desired to remove the cobblers, or whenever it is desired to open the sections of the housings for the removal or replacement of the rolls, the operation is conducted as follows: The inlet-valves of the hydraulics of the horizontals are opened and their outlet-valves are closed, thus forcing up the plungers, which immediately impart their vertical movement to the lifting-rods. This action of the lifting-rods swings the upper ends of the locking-clutches outward toward the sides of the housings, causing a reverse motion of their lower ends and withdrawing them from the rectangular slots in the lower

section. As soon as the upper ends of the clutches swing out until the lower are freed from their bearings in the lower section of the housings, the full strain is brought upon the pivots which connect the clutches with the upper section, and the latter is raised up to the height desired.

The operation of the verticals is as follows: The inlet-valves of the hydraulics are opened and the outlet-valves are closed, thus forcing the plunger upward, when it instantly communicates an upward movement to the lifting-rods attached to its face-plate and to the housing-cap and elevates the latter off of the head of the upper sections of the housings. At this point, when the cap has been elevated off the housing-head, the upward movement of the plunger causes the bottom of the sleeves on the face-plate to come in contact with the balls on the lower ends of the crank-rods, which, partaking of the upward movement, actuate the cranks and cause the upper sections of the housings to swing open upon their pivots, one of the sections carrying the housing-cap and upper joint of the cap-lifting rod with it during its outward movement.

In readjusting the horizontals into position it is merely necessary to open the outlet and close the inlet valves of the hydraulics, when the weight of the upper sections will cause them to settle into position, and the weight of the plungers will force the lower ends of the locking-clutches into the slots in the lower section of the housings and again lock both securely together. In readjusting the verticals into position the inlet-valve is closed and the outlet opened. As soon as the upper sections are released from the opening action of the ram, the weights or counterbalances attached to or suspended from the cranks of the pivots cause the two upper sections to swing together, and the housing-cap is then lowered down in position on the housings' head by the weight of the plunger.

The chief advantages of my improvement are:

First. Straighter rails are produced, requiring little or no labor for straightening.

Secondly. A large proportion of the bench-room is saved by getting less rails to straighten and to haul from the inspection-benches to the presses. Time is also saved by turning out more work fit to go out at once, by which the stock of rails in the yard may be kept low, so that a better control can be kept by the maker on the progress and execution of each order without having to stop to take stock of all the rails in the yard to be restraightened before the balance can be rolled, and as little if any straightening is required to be used the quality of the finished rail is far above that of the ordinary manufacture and the percentage of breakage during service is largely decreased.

Thirdly. The manner of locating the hydraulics or other equivalent lifts below the train relieves the roof of the building of the strain which would come upon it if they were over-

head, as was described by me in a recent application previously referred to.

Having described my invention, what I desire to claim, and secure by Letters Patent, is—

- 5 1. A machine for rolling rails provided with a series of sets of rolls having rail-forming grooves, the flange forming sections of the several grooves being located in horizontal planes so as to allow the rail or blank to rest upon its flange during its passage through the grooves, substantially as specified.
- 10 2. A sectional housing for a pair of vertical rolls having two upper vertical sections mounted on a lower section, in combination with a hydraulic ram or its equivalent located below the housings, and connected thereto by means of suitable intermediate mechanism to raise or open the upper sections of the housings.
- 15 3. The combination, with a set of horizontal rolls, of housings separable at or near a plane passing between the working faces of the rolls,

locking devices for connecting the housings, a hydraulic ram, and operating-rods connected with the locking devices and movable housing-sections so as to actuate both the locking devices and movable sections, substantially as and for the purpose specified. 25

4. A roll-train consisting of a series of rolls forming a continuous mill, wherein the successive rolls of the series are arranged in a line, and provided with grooves in each of the series of the shape and relative arrangement with reference to the reduction of the blank, substantially as specified, for forming the rail while resting on its base, or on the side which 30 in the finished rail forms the base, substantially as and for the purpose specified. 35
